UNITED STATES PATENT OFFICE.

JOHN GILL, OF JERSEY CITY, NEW JERSEY, ASSIGNOR OF ONE-HALF TO
HARRY G. PECKHAM, OF SAME PLACE.

HYDRAULIC ENGINE.

SPECIFICATION forming part of Letters Patent No. 606,337, dated June 28, 1898.

Application filed November 26, 1897. Serial No. 659,772. (No model.)

To all whom it may concern:

Be it known that I, JOHN GILL, a citizen of the United States, and a resident of Jersey City, in the county of Hudson and State of New Jersey, have invented certain new and useful Improvements in Hydraulic Engines, of which the following is a specification.

The invention relates to improvements in hydraulic engines; and it consists in the novel features and combinations of parts hereinafter described, and particularly pointed out in the claims.

I illustrate in the accompanying drawings the best embodiment of the invention known to me, and this embodiment of the invention comprises three vertical cylinders having discharge-ports at their lower end, a water-chest connected with all of said cylinders and provided with the inlet-valves for water and the outlet-valves for air, vertically-movable pistons within said cylinders and connected by their rods with the cranks radiating from a shaft to be driven, eccentrics upon said shaft adjacent to each of the cranks thereof, means intermediate said eccentrics and the aforesaid water and air valves whereby the latter may be operated from said eccentrics, and means under the control of a governor for tripping the gear connected with the water-valves upon any undue speed being attained in the engine.

The pistons within the cylinders are operated in one direction by the water entering the cylinders from the water-chest and are moved in the other direction by the cranks on the shaft to be driven and with which they are connected. The pistons within the cylinders are so disposed by means of the cranks with which they are connected that no two of said pistons have the same movement at the same time, and thus when, say, the middle one of said pistons is in its upper position another one of said pistons will be in its lower position discharging the water through the outlet-ports from its cylinder, and another one of the pistons will be starting upward toward the upper end of its cylinder. The cylinders are connected with suitable means for conveying away the water escaping through the discharge-ports of said cylinders.

The invention will be fully understood from

the detailed description hereinafter given, reference being had to the accompanying drawings, in which—

Figure 1 is a central vertical longitudinal section through an engine constructed in accordance with and embodying the invention. Fig. 2 is a side elevation of same. Fig. 3 is a top view of same. Fig. 4 is an enlarged end view, partly in vertical transverse section, of a portion of same. Fig. 5 is an enlarged top view of a portion of same, and Fig. 6 is a central vertical longitudinal section of same on the dotted line 6 6 of Fig. 5.

In the drawings, A designates the main supporting-frame; B, the water-chest; C, the vertical cylinders communicating with and extending downward from said chest; D, the belt-wheel, and E the crank-shaft driven by the piston-rods F, which extend upward from the three cranks G, formed in said shaft and are pivotally connected with the pistons H within the said cylinders C.

The cylinders C are vertical and parallel with one another, and each is formed with the discharge-ports I for the water, which enters the cylinders from the chest B and drives the pistons H downward. Each cylinder C is provided around its lower portion with the water receptacle or jacket J, and said jackets J, as more clearly shown in Fig. 3, have connected with them the independent pipes K, which at their outer ends are connected by a pipe L, communicating with a general delivery-pipe M, whereby the discharge from all of the cylinders C passes to said delivery-pipe M and thence escapes. The jackets J are independent of one another, and hence the discharge from any one of the cylinders C cannot interfere with the discharge-ports of any other cylinder C. The discharge-ports I of the cylinders C are of considerable area, so as to permit a very ready discharge of the water above the pistons H as soon as said pistons descend to uncover said discharge-ports I. The pistons H are hollow and in the form of cylinders, whereby the sides of said pistons H become of elongated form, adapting them to travel smoothly within the cylinders C and to properly cover and uncover the ports I. The upper ends of the piston-rods F are within the pistons H, as shown in Fig. 1. The

cranks G in the shaft E are at equal distances from one another, and to these cranks are pivotally connected the lower ends of the piston-rods F.

5 The water-chest B is directly supported upon the side frames A, and is preferably in one continuous piece and communicates with all of the cylinders C, the latter being open at their upper ends and secured directly to 10 the lower side of the water-chest B. The inlet to the chest B is through the supply-pipe N, and the outlet from said chest B to the cylinders C is through the ports O, which are supplied with the valves P, secured to the 15 vertical rods Q and adapted to be automatically seated by means of the springs R. The upper portion of the water-chest B is provided with the sleeves S, which receive and guide the said rods Q and furnish a stop for the 20 upper ends of the springs R, whose lower ends press directly upon the valves P. Each of the ports O, leading from the valve-chest B to the cylinders C, is provided with the valve P and rod Q. Each of the valve-rods 25 Q is, as more clearly illustrated in Figs. 4 and 6, provided with the inner valve-rod a, carrying the small downwardly-opening valve b, and also with the light spring d, which retains the valve b normally closed upward 30 against its seat formed at the lower central portion of the valve P. The valve b is an air-valve, and it will be automatically opened during the descent of the pistons H whenever the water does not entirely fill the cylinders 35 C above the pistons, and said valves b thereby prevent the creation of vacuums within the upper ends of the cylinders C. The upper ends of the cylinders C also communicate with the tubular openings T, which pass upward from said cylinders entirely through the water-chest B, as clearly illustrated in Figs. 1 and 6. The upper ends of the tubular openings T contain the downwardly-opening valves e, which are normally held against their seats 40 by means of the small coiled spring g, encircling the rods h of said valves e. The valves e are by the means hereinafter described positively moved downward into their open position at the time when the pistons H 45 are traveling upward, and thereby the air contained in the cylinders C is permitted to escape upward through the openings T and into the atmosphere.

The water-valves P and air-valves e are 50 positively operated by mechanism intermediate them and the crank-shaft E, and said mechanism is duplicated for each of the cylinders C and is illustrated on a somewhat-enlarged scale in Figs. 5 and 6.

60 Upon each side of each crank G of the crank-shaft E is an eccentric i, whose relation to the crank G is illustrated in Figs. 1 and 2. The eccentric i on the left-hand side of each crank G effects the opening of the water-valve P, and the eccentric i at the right-hand end of each crank G effects the opening of the air-valve e. The eccentric i at the left-hand side

of each crank G is by means of an eccentric-rod j connected with the rear end of a lever-arm k, whose front end is formed with the 70 sleeve m and is freely mounted upon the shaft n, extending lengthwise of the engine over the water-chest B. As more clearly illustrated in Fig. 5, the lever-arm K has formed upon it the sleeve o, by which and by means 75 of the screw p a pawl-arm q is pivotally secured to said lever-arm k. The pawl-arm q will move rearward when the left-hand eccentric i pulls downward on the rod j, and this movement of the pawl-arm q is made use 80 of to elevate the water-valve P and occurs when the piston H is at its upper position ready to be driven downward by the water entering the cylinder C through the port O, opened by the said valve P. The front end 85 of the pawl-arm q is hook-shaped, as illustrated in Fig. 4, and is adapted to engage a shoulder r on the disk s and to draw said disk rearward, and thereby cause the front end of the arm t, connected with the hub of said 90 disk s, to turn or move upward. The front end of the arm t is connected with the upper end of the stem Q of the valve P, and hence when the said arm t is moved upward it will elevate the valve-stem Q and the valve P and 95 open the port O, thereby permitting the water within the chest P to enter the upper end of the cylinder C and effect the downward movement of the piston within said cylinder. The disk s is, as shown in Fig. 5, mounted 100 upon the shaft n, above the water-chest B. The lever-arm k has a rocking motion and carries the pawl-arm q, and hence the motion of the pawl-arm q is generated wholly by the eccentric-rod j. When the eccentric-rod j is 105 by its eccentric pulled downward, the pawl-arm q will move rearward against the shoulder r on the disk s and turn said disk rearward, and thereby elevate the arm t and valve P, connected with said arm t. When the eccentric-rod j ascends, the pawl-arm q will be moved forward from the shoulder r on the disk s, and at such time the spring R, surrounding the valve-stem Q, will close the valve P and restore the arm t and disk s to 110 their normal position. The disk s and arm t are integral with one another, and hence the rearward rotation of the disk s will lift the arm t and the downward movement of the arm t, due to the action of the spring r, will 115 turn the disk s forward to its normal position. Each water-valve P is operated by exactly the means above described, and illustrated on an enlarged scale in Fig. 5, and hence it will be unnecessary to repeat this description of the parts as applied to each of the valves P.

The air-valves e are operated from the crank-shaft E by mechanism intermediate them and the eccentrics i, located at the right-hand side of the cranks G, and one set of this mechanism is illustrated on an enlarged scale in Fig. 5 and is duplicated for each air-valve e. The eccentric at the right-hand side of

each crank G is by means of the eccentric-rod A' connected with a lever-arm B', which is hung from the shaft n and is formed with the sleeve C', by means of which and the bolt 5 D' is pivotally secured the pawl-arm E', whose front end is adapted to engage a shoulder F', formed on the hub G', which carries the arm H', connected with the stem h of the air-valve e. The water-valve P is opened when the 10 piston in the cylinder is at its upper position ready to descend and is opened by the rearward pull of the pawl-arm q. The air-valve e is opened when the piston in the cylinder is at its lower position and is starting to ascend, 15 and hence the pawl-arm E' for operating the air-valve e comes into action when the pawl-arm q for the water-valve is at rest. The pawl-arm E' operates to open the valve e when it (said pawl-arm) is moving forward, and 20 the pawl-arm q operates to open the water-valve P when it (said pawl-arm) is moving rearward. The forward motion of the pawl-arm E' causes its front end to engage the shoulder F' and to turn the hub G' and lever-arm H' forward and downward, thereby causing 25 the air-valve e to descend from its seat and permit a ready escape of the air from the cylinder during the upward motion of the piston in said cylinder. During the forward 30 motion of the pawl-arm E' the spring g upon the valve-stem h will be compressed, and during the rearward motion of the pawl-arm E', due to the motion of its eccentric-rod A', the spring g will elevate the lever-arm H' and re- 35 store the valve e to its closed position and the hub G' and projection F' to their normal position to be acted upon again by the pawl-arm E' during the next ascent of the piston within the cylinder. The mechanism for operating the air-valve e is duplicated for each 40 of said valves.

There are three of the cylinders C, each having the discharge-ports I and piston H, and the valve-chest B for each of said cylinders C is furnished with the water-valve P and its connections and the air-valve e and its connections, and all of the air-valves e and all of the water-valves P are operated by the eccentrics upon the crank-shaft E, the 45 position of the eccentrics being varied to secure the proper timing necessary in the movements of the valves P and e. Each of the valves P is, as above described, provided with the air-valve b. The valves b are not operated by means connected with the crank-shaft E, but simply in one direction by the pressure created by the downwardly-moving piston H and in the other direction by the force of the spring d, the latter coming into operation af- 50 ter the force created by the downwardly-moving piston H has ceased to exist. The valve P is opened to admit the water to the cylinder C and then closed to cut off the water therefrom. The valve e is opened during the 55 ascent of the piston H within the cylinder C to permit of the escape of the air from the

cylinder under the action of the then upwardly-moving piston H, and the air-valve b is opened by the then downwardly-descending piston H simply to prevent the formation of 70 any vacuum in the upper end of the cylinder C due, for instance, to the valve P closing before the piston H shall have reached the discharge-ports I.

The shaft n serves to support the front ends 75 of the lever-arms j and B' and the rear ends of the lever-arms t and H', as above explained, and said shaft n is also important in that it forms a part of the mechanism by which, upon the crank-shaft E attaining undue speed, the 80 valves P may be closed to cut off the water from the cylinders C, and thus restore the motion of the shaft E to its normal speed. The shaft n is connected by an arm I' with the sleeve J', connected with the governor K' and 85 adapted to slide vertically upon the rod L'. The rod L' is mounted in suitable bearings, as illustrated in Fig. 4, and its lower end is provided with the bevel gear-wheel M', which is in mesh with the bevel gear-wheel N', secured 90 upon the shaft O', having upon its outer end the belt-wheel P', as shown more clearly in Figs. 1 and 4. The belt-wheel P' on the outer end of the shaft O' is connected by a belt Q' with the belt-wheel R', secured to one end of 95 the crank-shaft E. The motion of the crank-shaft E thus through the belt-wheel R', the belt Q', belt-wheel P', shaft O', and beveled gear-wheels N' M' is communicated to the vertical rod or shaft L', carrying the gov- 100 ernor. Upon the shaft E attaining an undue speed its motion will be communicated through the intermediate gearing just described to the vertical rod or shaft L', carrying the governor K', and upon this taking 105 place the sleeve J' will, in a well-known manner, be caused to ascend and in ascending will pull upward upon the rear end of the lever-arm I', and thereby rock the shaft n forward and downward, and the effect of this motion 110 of the shaft n will be to cause the projections S' on said shaft n or upon sleeves carried by said shaft to move below the front ends of the pawl-arms q and trip said pawl-arms q from their engagement with the shoulders r 115 on the disks s, thus releasing the valves P from the influence of said pawl-arms q and permitting the springs R to close said valves P, whereby the water will be cut off from the cylinders S and the speed of the crank-shaft 120 E will be brought to its normal condition. Upon the crank-shaft E being restored to its normal speed the sleeve J' on the vertical rod or shaft L will move downward and through the lever-arm I' turn the rock-shaft n up- 125 ward and rearward to its normal position, and thereby the pawl-arms q will be enabled to perform their usual functions. When the pawls E' have moved forward and held the air-valves e open a sufficient length of time, 130 the laterally-extending portion of the front ends of said pawls E' ride over and are ele-

vated by the arms *x*, and upon this taking place the valves *e* automatically close, the pistons then being in their upper position.

What I claim as my invention, and desire to secure by Letters Patent, is—

1. A hydraulic engine comprising the series of cylinders having the free discharge-ports at their lower end and the inlet and outlet openings for water and air respectively at their upper end, combined with the crank-shaft, the pistons within said cylinders, the piston-rods connecting the cranks of said shaft with said pistons, valves for said inlet and outlet openings, means for operating said valves, cut-off mechanism for said inlet-valves, and the water-chest communicating with said cylinders and also with a source of water-supply; substantially as set forth.
2. A hydraulic engine comprising the water-chest communicating with a source of water-supply, and the three cylinders connected at their upper end with said water-chest and at their lower end having the free discharge-ports for water, combined with the crank-shaft, the pistons within said cylinders, the piston-rods connecting the three cranks of said shaft with said pistons, inlet-valves controlling the inlet-ports for water from said water-chest to said cylinders, means for permitting the escape of the air from said cylinders during the ascent of said pistons, cut-off mechanism for said valves, and means for opening and closing said valves; substantially as set forth.
3. A hydraulic engine comprising the water-chest communicating with a source of water-supply, and the three cylinders connected at their upper end with said water-chest and at their lower end having the free discharge-ports for water, combined with the crank-shaft, the pistons within said cylinders, the piston-rods connecting the three cranks of said shaft with said pistons, inlet-valves controlling the inlet-ports for water from said water-chest to said cylinders, the inlets adapted to admit air to said cylinders during the descent of the pistons, means for permitting the escape of the air from said cylinders during the ascent of said pistons, and means for

operating said valves; substantially as set forth.

4. A hydraulic engine comprising the water-chest communicating with a source of water-supply, and the three cylinders connected at their upper end with said water-chest and at their lower end having the free discharge-ports for water, combined with the crank-shaft, the pistons within said cylinders, the piston-rods connecting the three cranks of said shaft with said pistons, inlet-valves controlling the inlet-ports for water from said water-chest to said cylinders, the tubular openings extending from the upper ends of said cylinders up through said water-chest to the atmosphere, valves controlling said tubular openings and adapted to open during the ascent of said pistons, and means for operating said inlet and outlet valves; substantially as set forth.

5. A hydraulic engine comprising the series of cylinders having the free discharge-ports at their lower end and the inlet-opening for water at their upper end, combined with the crank-shaft, the pistons within said cylinders, the piston-rods connecting the cranks of said shaft with said pistons, the valves for said inlet-openings, the water-chest communicating with a source of water-supply and connected with said cylinders, the rock-shaft extending above and lengthwise of said water-chest, the governor connected with said crank-shaft and said rock-shaft, the eccentricities on said crank-shaft, the eccentric-rods connected therewith, the lever-arms connected with said rods and hung from said rock-shaft, the pawl-arms carried by said lever-arms, the projections on said rock-shaft below said pawl-arms for tripping the latter, and the lever-arms connected with the stems of said valves and adapted to be operated by said pawl-arms; substantially as set forth.

Signed at New York, in the county of New York and State of New York, this 24th day of November, A. D. 1897.

JOHN GILL.
